[57] CLAIM

The ornamental design for a shingle removing tool, as shown.

DESCRIPTION

FIG. 1 is a front view of the shingle removing tool of the present invention;

FIG. 2 is a back view of the shingle removing tool of FIG. 1;

FIG. 3 is a left side view of the shingle removing tool of FIG. 1;

FIG. 4 is a right side view of the shingle removing tool of FIG. 1;

FIG. 5 is a top plan view of the shingle removing tool of FIG. 1; and,

FIG. 6 is a bottom plan view of the shingle removing tool of FIG. 1.

The handle has been shown fragmentarily to indicate an indeterminate length.
